Primary Examiner — Brett Miller(74) *Attorney, Agent, or Firm* — PV IP PC; Wei Te Chung; Zhigang Ma(57) **CLAIM**

We claim the ornamental design for a booth, as shown and described.

DESCRIPTIONFIG. 1 is a front view of a booth showing our new design;
FIG. 2 is a top view thereof;
FIG. 3 is a right side view thereof;
FIG. 4 is a left side view thereof;
FIG. 5 is a back view thereof;
FIG. 6 is a bottom view thereof;
FIG. 7 is a reduced perspective view thereof;
FIG. 8 is a cross-section view along line 8-8 of FIG. 2;
FIG. 9 is a cross-section view along line 9-9 of FIG. 2;
FIG. 10 is a cross-section view along line 10-10 of FIG. 1; and,
FIG. 11 is a reduced exploded view thereof.
The broken lines in the drawings are for environmental purposes only and form no part of the claimed design. The dot-dash broken lines in the drawings represent the bounds of the claimed design.**1 Claim, 11 Drawing Sheets**(56)
